Primary Examiner — Eliza Z Harvey*Assistant Examiner* — Kayla Marie Bennett(74) *Attorney, Agent, or Firm* — CBM Patent Consulting, LLC(57) **CLAIM**

The ornamental design for a snap assembly, as shown and described.

DESCRIPTION

FIG. 1 is a top view of a snap assembly showing my new design;

FIG. 2 is a bottom view thereof;

FIG. 3 is a front view thereof;

FIG. 4 is a rear view thereof;

FIG. 5 is a left side elevational view thereof;

FIG. 6 is a right side elevational view thereof;

FIG. 7 is a perspective view thereof; and,

FIG. 8 is a top, front, left side perspective view of the snap assembly, showing my new design; the broken line showing of a flat belt is for illustrative purposes only, and forms no part of the claimed design.

1 Claim, 7 Drawing Sheets(56)
